INVENTOR
Arthur B. Modine
By Burton DeSleeth Atty:

UNITED STATES PATENT OFFICE.

ARTHUR B. MODINE, OF RACINE, WISCONSIN.

RADIATOR.

Application filed May 10, 1920. Serial No. 380,214.

To all whom it may concern:

Be it known that I, ARTHUR B. MODINE, a citizen of the United States, residing at Racine, in the county of Racine and State of Wisconsin, have invented certain new and useful Improvements in Radiators, of which the following is a description.

My invention belongs to that general class of devices known as radiators which are generally used on automobiles, trucks, tractors and the like, in connection with the cooling systems of internal combustion engines. The invention has among its objects the production of a device of the kind described that is simple, durable, convenient, efficient, attractive and satisfactory for use wherever found applicable. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Fig. 1 is a view in elevation of a radiator embodying my invention;

Fig. 2 is a sectional view taken substantially on line 2—2 of Fig. 1;

Fig. 3 is a sectional view taken substantially on line 3—3 of Fig. 1;

Fig. 4 is an enlarged view of the lower radiator tank;

Fig. 5 is a view in elevation of a slightly modified construction; and

Fig. 6 is a sectional view taken substantially on line 5—5 of Fig. 5.

Referring to the drawings, 1 represents a chambered part or tank of suitable size, shape and material, which is preferably provided with an inlet pipe 2 to which a hose pipe or the like may be attached connecting the same with the cooling system. As shown, part 1 is also provided with a tubular part 3, the same constituting the filler tube or opening similar to the constructions now in use.

Associated with the part 1 is a chambered part 4 communicating with the part 1, and the two forming substantially a tank consisting of two communicating parts. Associated with the part 4 is a chambered part

5, which constitutes what may be termed a lower tank. As shown, extending between and connecting the tanks are the desired number of tubes 6 through which water or other cooling fluid may pass from the tank 4 to the tank part 5, and in so doing, be cooled by the air passing or drawn between the tubes. Fins or plates 7, of a desired form, are preferably arranged on the tubes so as to increase the radiating area and deflect the air. The part 5 is provided with an outlet, as shown, through the pipe 8, which may be connected to a suitable part in the system from which the fluid is to be cooled.

In the construction shown in Figs. 1 and 3, the tank parts 1 and 4 are provided with openings 9 and 10 which register with each other, a gasket or the equivalent 11 being arranged between the two, and the parts are secured together by bolts 14 of which there may be any desired number. As shown, what may be termed a spider 12 is arranged at each of the openings 10, the same being preferably secured on the inner side of the tank part 4, and of a size and material sufficiently rigid so as not to yield. The part 1 is recessed as at 13, and the bolts 14 positioned with their heads in the recesses and extended through the tank 1 through the opening in part 15 of the spider 12, the central part 15 of the spider being preferably threaded to engage the bolt threads. I have shown the tank parts 4 and 5 secured together by the bars 16, so that there is substantially no strain on the tubes 6. To support or carry the radiator, I provide a U-shaped frame consisting of the side parts 17 connected at 18, which parts 17 are preferably secured to the upper tank 1 in any suitable manner. The frame may be secured in place, when desired, or supported by means of the lugs 22. Referring particularly to Fig. 2, one or more springs 19 are shown arranged between frame part 18 and the tank, the tank 5 being preferably provided with a flange 20 and the cross part 18 of the frame with the flange 21, between which is arranged the springs 19. Obviously these springs supplement the side bars 16, and also take considerable strain from the bolts 14, due to the weight of the parts and contained fluid, and they give some resiliency or flexibility to the construction in case of jars, strains or twisting, so that leaks about the ends of the tubes and between the tanks are

obviated. The radiator tank and frame parts, at the front side, may be covered by a cover plate 23, secured to the frame 17-18 by bolts, screws, or in any other preferred manner, (not shown), the cover plate, however, being open or cut away at 24, so as to expose the tubes 6. This cover plate 23 may be large enough to cover the top of the tank and sides and bottom, if so desired. 10 In the construction shown, however, I have merely arranged the same over the front. Part 1 and the frame constitute a unit part and parts 4 and 5 constitute another unit.

As is most clearly shown in Figs. 2 and 15 4, the discharge pipe 8 may be so connected to the tank 5 that it may be easily detached by working at the front of the radiator. In the construction shown, a spider 12' is arranged on the tank part 5 and the outlet 20 pipe 8 is provided with a spider 8', 11' being a gasket arranged at the opening from the tank. The parts are secured together by a bolt 14' extending through the spiders 12' and 8' and to the front side of the tank 25 part 5. The tank may be reinforced by the rods 24' spacing the spiders 12' apart so that the tightening up on the bolt and the drawing of pipe 8 tightly against the tank will not cause the collapse of the tank. The 30 construction is substantially similar to the connection between the tank parts 1 and 4. It will be noted that by removing the bolts 14, 14 and 14', the radiator may be quickly disassembled and the tubes and plates 35 taken out for repair or replacement.

In the slightly modified construction shown in Figs. 5 and 6, 25 represents a tank part having the inlets 26 and 27, the same being provided with the flange 28. A co-operating tank part 34, flanged as at 29, is 40 provided, the parts being secured together by bolts 33', or the equivalent, extending through the flanges. Obviously tank part 34 may be of any desired size. If only a 45 flat plate having an opening through, it would serve as well. If desired, a gasket 32 may be arranged as shown. Depending from the tank part 34 are tubes 30, on which may be arranged the plates 31. Arranged 50 at the lower end of the tubes 30, is a tank 35 having an outlet 36, the tanks being connected together by the side bars 37, or the equivalent. In this construction I provide a frame 38-39-38, which is secured to the 55 end flanges on part 25, by bolts 33', or the equivalent. Springs 40 or the equivalent are arranged between the frame part 39, and the tank 35, similar to the construction previously described and serve to relieve strain 60 in the bolts 33. The frame is provided with the flanges or lugs 41, by means of which the radiator may be secured in place and supported as desired.

In the construction shown in Fig. 1, water 65 or other cooling fluid enters the pipe 2 from

the circulating system, passes through tank parts 1 and 4, and through the tubes 6 into tank 5, and thence out through 8 back to the desired point in the system. As the same passes through the tubes, the same is cooled, or that is, the heat therein is dissipated. In the construction shown in Figs. 4 and 5 the cooling fluid enters at 26 and passes through the parts 25 and 34, and through tubes 30 into part 35, from whence it is discharged at the outlet 36. 70 75

It will be noted that with both of these constructions the radiator consists of two associated tanks connected by tubes and an associated chamber part or tank connected to one of the other tanks, all of the parts being suitably secured together. The parts 4 and 5 and tubes may be standardized in various sizes, as may also be the parts 34 and 35 and tubes, and the parts 1 and 25 may be varied in contour, size or capacity, depending upon the particular automobile or the like upon which the radiator is to be used. On the other hand under the circumstances, parts 1 and the frame and 25 and the frame may be standardized, and the radiator element consisting of the two tanks and connecting tubes, may be modified or varied for different makes of cars, depending upon the preference of the manufacturer thereof. 80 85 Various combinations are therefore possible with either construction, in case it is desired to repair the radiator tubes or parts, the tanks 4 and 5 and tubes, or 34 and 35 and tubes may be removed from the top tank parts and frame without removing the entire assembly. This is of considerable advantage in some cases, as where manufacturers use a standardized part 1 or 25 and frames, 90 the tanks and connecting tubes may be interchanged with another of the same type, 95 whenever desired. 100 105

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned. 110 115

What I claim as new and desire to secure by Letters Patent is:

1. In a radiator, a plurality of tubes, 120 tanks each extending the full width of the radiator front arranged at each end of said tubes and communicating therewith, a chambered part associated with and communicating with only one of said tanks, the other of said tanks having no similar chambered part associated therewith, said chambered part having an inlet, and means for detachably securing said chambered part and tanks together comprising bolts extending through said chambered part and engag- 125 130

- ing a portion of the top part of the tank associated therewith.
2. In a radiator, a plurality of upright tubes, tanks each extending the full width of the radiator front arranged at each end of said tubes and communicating therewith, a chambered part associated with and communicating with only one of said tanks, the other of said tanks having no similar chambered part associated therewith, said chambered part having an inlet, means for detachably securing said chambered part and tanks together comprising bolts extending substantially vertically through said chambered part and engaging a portion of the top part of the tank associated therewith, and means for yieldably supporting said part.
3. In a radiator, a plurality of tubes, tanks each extending the full width of the radiator front arranged at each end of said tubes and communicating therewith, a chambered part associated with and communicating with one of said tanks, said chambered part having an inlet, means for detachably securing said chambered part to said tanks comprising bolts extending through said chambered part, and a spider within the top part of the tank associated therewith and engageable by said bolt.
4. In a radiator, a tank comprising two communicating chamber parts, a second tank associated therewith and connected with only one of said parts, tubes connecting said first-mentioned chamber parts, means for securing said second tank to the upper of said chamber parts of the first-mentioned tank, a frame spaced from the bottom and sides of said first mentioned tank for supporting said radiator, and resilient means between said frame and the lower chambered part of said first-mentioned tank to yieldably support said tanks and permit relative movement between the bottom one of said chambered parts and said frame due to expansion therebetween.
5. In a radiator, a tank comprising two communicating chambered parts, a second tank associated therewith and connected with one of said parts, tubes connecting said tanks, means for securing said tanks together, a frame about said tanks and spaced from the bottom and sides thereof, and resilient means between the bottom of the lower tank and the frame for yieldably supporting the radiator so that said lower tank may move relatively to the frame.
6. In a radiator of the kind described and in combination, a unit comprising a tank and a frame connected thereto, and a unit comprising a plurality of tubes and tank parts connected therewith, means for securing said units together, and means for detachably securing a discharge pipe to one of said tank parts, whereby it may be detached from the front of the radiator.
7. In a radiator of the kind described and in combination, a unit comprising a tank and a frame connected thereto, and a unit comprising a plurality of tubes and tank parts connected therewith and a discharge pipe arranged on one of said tank parts, means for securing said units together comprising a spider at the end of said pipe adjacent its associated tank, and a bolt extending through said tank and engageable with said spider, and means for reinforcing and bracing one of said tank parts from within comprising spiders at each of its inner sides, and spacer rods engageable at their ends with said spiders.
8. In a radiator of the kind described and in combination, a unit comprising a tank and a frame connected thereto, and a unit comprising a plurality of tubes and tank parts connected therewith, means for securing said units together, means for detachably securing a discharge pipe to one of said tank parts, and means for reinforcing and bracing said last mentioned tank part from within comprising spiders at each of its inner sides, a bolt upon which the spiders are mounted, said bolt being engageable with said discharge pipe to secure it in place, and spacer rods engageable at their ends with said spiders.
- In testimony whereof, I have hereto signed my name in the presence of two subscribing witnesses.
